UNITED STATES PATENT OFFICE.

JAMES C. SERGESON, OF PHILADELPHIA, PENNSYLVANIA.

SHUTTLE.

1,090,572.

Specification of Letters Patent. Patented Mar. 17, 1914.

Application filed March 17, 1913. Serial No. 754,677.

To all whom it may concern:

Be it known that I, JAMES C. SERGESON, a citizen of the United States, residing in the city and county of Philadelphia, State 5 of Pennsylvania, have invented a new and useful Shuttle, of which the following is a specification.

My invention consists of a loom shuttle which is provided with plates for the frictional engagement therewith of the yarn or thread passed between the same, the upper or outer plate thereof being subjected to pressure which may be varied so as to adjust the tension on the yarn or thread to the required extent in running it out of the shuttle for service in the loom.

It further consists also of details of construction as will be hereinafter set forth.

The invention is satisfactorily illustrated 20 in the accompanying drawings, but the important instrumentalities thereof may be varied, and so it is to be understood that the invention is not limited to the specific arrangement and organization shown and 25 described.

Figure 1 represents a top or plan view of a portion of a shuttle embodying my invention. Fig. 2 represents a side elevation thereof. Fig. 3 represents a longitudinal section of a portion on line $x-x$ Fig. 2. Fig. 4 represents a transverse section on line $y-y$, Fig. 3. Fig. 5 represents a transverse section on line $z-z$ Fig. 3. Fig. 6 represents a side elevation of the friction plates 30 and connected members. Fig. 7 represents a perspective view of said plates in separated condition. Fig. 8 represents a section on line $a-a$ Fig. 6.

Similar numerals of reference indicate 40 corresponding parts in the figures.

Referring to the drawings:—1 designates the body of a loom shuttle, and 2 designates the nose portion thereof. In the side of said body near said portion is the recess 3 which 45 is occupied by the friction plates 4, which are imposed one on the other, the upper plate having bearing upon it the spring 5 which occupies a position in the opening 6 in the nose portion 2, said opening being 50 at a right angle to the recess 3 and contains also the screw 7 which passes through said spring and opening 8 in said plates 4 and has its threaded portion engaging with the body or nose portion below said recess. The 55 head 9 of said screw is seated upon the up-

per end of the spring 6 and so retains the latter in place while also serving to adjust the tension of the spring, which tension is imparted accordingly to the plates 4 especially to the upper plate thereof. In said 60 plates 4 are also the openings 10 which receive the pin 11, the latter being secured in the nose portion 2 and serving to guide the upper plate 4 and retain the plates in position in the recess 3. The ends of the 65 plates toward the nose portion 2 are rounded or beveled as at 12 and the sides of the upper plate have depending therefrom the horns 13 which are separated forming the throat 14, said horns 13 freely embracing 70 the lower plate so as to guide the upper plate in its rising and lowering motions from and to the lower plate, said upper plate having also on the side opposite to the horns 13, the depending horn 15 which 75 freely embraces the lower plate and assists in guiding said upper plate in said rising and lowering motions.

16 designates a finger which occupies the recess 16^x in the side of the nose portion 2 and has a shank or limb 16^{xx} which extends transversely into said nose portion, and is tightly engaged therewith, thus firmly retaining said finger in position. The recess 16^x is in communication with the diagonally 80 extending throat 17 in the top of the nose portion 2, said throat being in communication with the longitudinally-extending passage 18 which is in the side of said nose portion, said passage 18 extending to the recess 90 3 and communicating therewith at the rounded ends 12 of the plates 4.

It will be seen that when the yarn or thread from the bobbin is to be threaded on the shuttle, it is directed behind the finger 16 and drawn forwardly whereby it enters the throat 17 and passage 18 and so reaches the ends 12 of the plates 4 and when it enters between said ends and lifts the upper plate 4, passes around the limb 16^{xx} of 100 the finger 6 as a post therefor and also around the unthreaded portion of the screw 7 as another post while being between said plates 4 when it plays out from the plates, through the throat 14 to the loom, it being 105 evident that said plates 4 impart the proper tension to the thread or yarn as the thread or yarn runs between the same, the upper plate yielding to the thread or yarn as occasion may require, while the tension there- 110

on may be adjusted by the spring 5 due to the proper rotation of the screw 8 as herein-before-referred-to. It will be seen also that the yarn or thread in its motion is retained 5 in the throat 14 and so guided by the horns 13, whereby it will pass through the plates 4 without liability of entering the recess 3 or contacting with the walls thereof.

Having thus described my invention what 10 I claim as new and desire to secure by Letters Patent, is:—

1. In a loom shuttle, a body having a recess in the eye thereof, friction plates therein and imposed one on the other and one 15 having on its side separated depending horns forming a throat therebetween, said horns freely embracing and receiving the other plate.
2. In a loom shuttle, a body having a recess, friction plates therein and imposed one upon the other and one having on its face 20 depending horns forming a throat therebetween, said horns freely embracing and receiving the other plate and said plate being

further provided with a depending horn on 25 the face opposite the first-named horns.

3. In a loom shuttle, a body having a recess, friction plates therein and imposed one upon the other and one having on its face 30 separated depending horns forming a throat therebetween, said horns freely embracing and receiving the other plate and said plate being further provided with a depending horn on the face opposite the first-named horns, said plates having their ends rounded. 35

4. In a loom shuttle, a body having a recess therein in the eye thereof, friction plates in said recess, one plate being imposed separately on the other, means for adjusting pressure on said plate, means in addition to 40 said adjusting means for guiding said plates on each other, and a finger in said body adjacent to said plates, said finger having a limb at an angle thereto on said body.

JAMES C. SERGESON.
